UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 14,829, dated February 26, 1884.

Application filed January 23, 1884. Term of patent 3½ years.

To all whom it may concern:

Be it known that I, SARAH JANE SHIELS, of the city, county, and State of New York, have invented and produced a new and original Design for a Pattern of a Lady's Costume, (numbered 9,034;) and I do hereby declare that the engraved prints accompanying this specification convey to any one accustomed to using paper patterns a clear understanding of how a garment made up by the pattern will appear.

The design shows a walking-skirt that displays a front drapery extending to the bottom, slashed at the lower edge, and gathered at the side edges; shorter side draperies exhibiting three crosswise plaits near the top; a plaited fan in the lower part of the skirt at each side of the front drapery; a closely-fitted

basque-front, pointed at the center and arched at the sides; a closely-fitted polonaise-back displaying plaits at the lower ends of its middle three seams, and loopings at the center and front edges; a lapel-collar extending to the bottom of the basque-fronts; a standing collar, and coat-sleeves.

What I claim as my invention, and desire to secure by Letters Patent, is—

The design for a lady's costume, as shown in the engraved prints accompanying this specification.

SARAH JANE SHIELS.
